UNITED STATES PATENT OFFICE.

ROBERT REX DOWNIE, OF BEAVER FALLS BOROUGH, PENNSYLVANIA, ASSIGNOR TO
KEYSTONE DRILLER COMPANY, A CORPORATION OF PENNSYLVANIA.

DITCHER-SCOOP ASSEMBLY.

Application filed January 3, 1927. Serial No. 158,738.

This invention relates to excavating machines of the type disclosed in my Patent No. 1,511,114 dated October 7, 1924, and among other objects, aims to provide a construction 5 for securing the scoop rigidly upon the end of the ditcher stick, while permitting ready removal of the scoop and replacement with another of a different size.

The invention may be understood by reference to one illustrative embodiment shown in the accompanying drawings, in which:

Fig. 1 is an elevation of the ditcher stick and scoop viewed from the outer end of the scoop, and showing particularly the scoop 15 bracing means;

Fig. 2 is a side elevation of the same, showing the scoop braces and also the scoop attaching means;

Fig. 3 is an elevation of the scoop, viewed 20 from the inner or toothed end, and omitting the major part of the ditcher stick;

Fig. 4 is a section on line 4—4 of Fig. 3;

Fig. 5 is a section on line 5—5 of Fig. 3;

Fig. 6 is a section on line 6—6 of Fig. 2; 25 and

Fig. 7 is a section on line 7—7 of Fig. 1.

In digging ditches and trenches with machines of the type disclosed in my Patent 1,511,114, it is highly advantageous to construct the ditcher stick and scoop so that the scoop may be removed from the end of the stick and replaced by another scoop of a different size better suited for the work to be done. For example, in digging a narrow trench as for laying pipe, the work may be done most satisfactorily by a narrow scoop of a width of 20 in. or under. On the other hand, when excavating for a drainage ditch, it is desirable to excavate as much material as possible during each cycle of the machine, and hence in such work scoops having a width of 60 in. or more are frequently employed. As machines of the indicated type are generally owned by contractors, who usually desire to be in a position to undertake any kind of an excavating job, it is distinctly advantageous for the manufacturer to offer a complete line of scoops of widths ranging say between 15 in. and 70 in., the maximum width used being determined by the power and ballast limitations of the machine which is to handle the scoop. Both for economy of investment by the contractor and for economy of manufacture, the present invention makes it possible to secure any scoop within the se-

lected range of scoop widths for attachment to a commonly suitable ditcher stick, without modification of the ditcher stick or the use of any special detachable parts peculiar to any size of scoop. While making possible the attachment of scoops of varying widths to a standardized ditcher stick, the invention insures a rigid connection between the stick and the selected scoop, even under the heavy reversing stresses set up during excavation. 65

Referring more specifically to the drawings, there is shown the upper end of a boom 10 which is pivotally connected as at 11 to a ditcher stick 12. At the upper end of the ditcher stick a yoke 13 carries a sheave 14, 70 about which a power line passes (not shown), while at the lower end of the ditcher stick is the scoop 15, secured in a manner to be presently described. A hauling bail 16 is pivoted to the scoop and a power line (not shown) 75 connected to the hauling bail is operated synchronously with or independently of the power line which passes around sheave 14, causing the scoop to move through the material to be excavated.

The scoop 15 is of the bottom dumping type having sides 17, a bottom 18 pivoted as at 19 and an end plate 20 carrying a latch 21 for the bottom. Excavating teeth 22, 23 are at the forward or open end of the scoop so as to facilitate penetration of the material to be excavated. The scoop is also claimed in my copending applications Serial Nos. 111,002, 151,350 and 158,739, the last-named application being directed particularly to the 90 side rake teeth 23.

In excavating any material, the parts connecting the scoop and ditcher stick are subjected to severe stresses. Because of the inherent liability of play incident to the use 95 of bolts subjected to loads in shear, it is highly desirable to employ attaching bolts subjected to tension only as means to prevent play between the scoop and stick under the reversing stresses. Especially is this desirable if the scoop is to be used in excavating in rocky ground where it will be subjected to exceptionally severe reversing stresses.

In the specific embodiment of the invention the scoop has a bail 24 permanently secured to the sides 17 and extending transversely across the scoop above the top of the same. Preferably the transverse portion of the bail is substantially flat, as shown. To transmit the downward thrust of the stick 110

on the scoop so far as possible through the vertical legs of the bail, the stick has an enlarged base or foot beneath which the bail is designed to be secured by means to be described. To prevent possible buckling of the bail under stresses imposed by the stick, one or more angle plates 25 are secured above the bail so as to extend for substantially the entire width of the scoop. If two angle plates 10 are employed, as shown, they are arranged so that two opposed legs are vertical and are spaced apart a sufficient distance to receive the end of the ditcher stick, while the horizontal legs or webs of the angle plates are 15 juxtaposed one above the other. Primarily to prevent undue vibration of the end wall 20 of the scoop, one or more end wall braces 26 are secured to the end wall and to one of the angle plates as best shown in Fig. 2. These 20 braces are claimed in my copending application Serial No. 151,350.

The ditcher stick is preferably made of two channels or other structural steel members 25 permanently secured together and spaced somewhat apart, as shown. At the lower end of the ditcher stick a large foot or base is provided by means of a plurality of angular foot members 27, said angular foot members preferably being secured both inside and outside 30 of each of the channels. These angular foot members are of such width that they may be received within the channel provided by the angle plates 25 and the horizontal legs of the foot members extend over the upper surface 35 of the horizontal leg of the upper angle plate. To permit temporary but rigid connection between the bail and the ditcher stick, bolt holes are drilled through the bail, the angle plates and the horizontal legs of the foot 40 members, and bolts 28 are passed through these holes to connect the parts together. The bolts 28 are parallel to the longitudinal axis of the ditcher stick. It will be obvious that the bolts are quite accessible and therefore 45 easily removed when it is desired to de-mount a scoop. Because of the peculiar construction and arrangement of the parts described, the bolts 28 are not subjected to shearing stresses during use of the scoop in excavating and therefore no play develops 50 between the scoop and the stick even when the scoop is used under exceptionally severe conditions.

Further to strengthen the connection between the scoop and the ditcher stick, one or more scoop braces 29 are used. These scoop braces are permanently secured at their upper ends to a midpoint of the ditcher stick and are bolted to the end plate of the scoop so as 55 to form a triangular truss with the scoop and ditcher stick. To provide a footing of adequate strength for the scoop braces, a shoulder member 30 is riveted to the outside of the end plate 20 near the top of the scoop. Where 60 two scoop braces are used, a forged or cast

U-shaped foot member 31 is permanently secured to the lower ends of both scoop braces, as best shown in Fig. 7, with a face abutting against the shoulder 30. Removable bolts 32 extend through the shoulder 30 and the lower 70 face of the U-shaped foot member, the bolts being parallel to the length of the braces.

To prevent possible slight twisting of the scoop on the end of the ditcher stick, with consequent abrasion between the foot of the stick and the channel structure of the bail, one or more clamping bolts 33 may be employed to draw together the intermediate portions of the vertical legs or flanges of the angle plates 25. Such a bolt or bolts in conjunction with the base of the stick, also prevent buckling of the vertical legs, especially when each bolt is surrounded by a spacer tube 34, which is gripped securely between the vertical legs. The number of bolts 33 to be 80 used will depend on the width of the scoop, to which the length of the angle plates are directly proportioned.

It will be clear that neither the bolts 28, which secure the bail to the ditcher stick, nor 90 the bolts 32 which secure the scoop braces 29 to the scoop, are subjected to shearing stresses during excavation. The parts are so designed and arranged that the only elements subjected to shearing stresses are rivets, which are of 95 sufficient number and of adequate strength to resist said stresses. In short, all bolts relied upon for securing the parts are arranged so as to be parallel to the direction of the stresses which fall upon them. The practical result 100 is that the scoop does not become loose on the stick, which is highly advantageous especially in hard digging or when using the scoop to break shale and rock by a series of maul-like blows.

Obviously the present invention is not restricted to the particular embodiment thereof herein shown and described. Moreover, it is not indispensable that all the features of the invention be used conjointly since they may 110 be employed advantageously in various combinations and subcombinations.

What is claimed is:

1. An assembly of the class described comprising, in combination, a ditcher stick; an 115 excavating scoop having a bail extending transversely across the open top and secured to the sides of the scoop; a pair of angle plates secured to the bail; and a rigid and enlarged footing secured to the ditcher stick; said footing being removably secured to and above the angle plates on the bail.

2. An assembly of the class described comprising, in combination, a ditcher stick; an 120 excavating scoop having a bail extending transversely across the open top and permanently secured to the sides of the scoop; an angle plate secured to the bail, and constructed and arranged to conform to the shape of 125 and extend over the upper end of the bail 130

- and to distribute the thrust from the stick over the major part of said upper end; and removable fastening elements for securing the bail and stick together while permitting detachment of the scoop when desired.
3. An assembly of the class described comprising, in combination, a ditcher stick; an excavating scoop having a bail extending transversely across the open top and secured to the sides of the scoop; a pair of angle plates on the bail and so arranged that two opposed webs form a channel to receive the stick, and the other two webs are juxtaposed, one above the other, and permanently secured to the bail; the two juxtaposed webs having approximately the width and length of the transverse portion of the bail; and bolts removably securing the bail and stick together; the construction permitting the transmission of the downward stresses imposed by the stick directly through the bail to the scoop without shearing stresses imposed on the attaching bolts.
4. An assembly of the class described comprising, in combination, a ditcher stick; an excavating scoop having a bail extending transversely across the open top and permanently secured to the sides of the scoop; a pair of angle plates extending along the transverse portion of the bail and so arranged that two webs of the angle plates are juxtaposed, one above the other, and permanently secured to the bail; bolts for connecting the angle plates and bail to the stick; the construction permitting the transmission of the downward stresses imposed by the stick directly through the bail to the scoop without shearing stresses imposed on the attaching bolts.
5. An assembly of the class described comprising, in combination, a ditcher stick; an excavating scoop having a bail extending transversely across the open top and secured to the sides of the scoop; a pair of angle plates secured to the bail and so arranged that two webs are juxtaposed, one above the other, and permanently secured to the bail; foot members permanently fastened to the stick at its end; bolts for connecting the stick to the bail by means of said foot members; the construction permitting the transmission of the downward stresses imposed by the stick directly through the bail to the scoop without shearing stresses imposed on the attaching bolts.
6. An assembly of the class described comprising, in combination, a ditcher stick; an excavating scoop having a bail extending transversely across the open top and permanently secured to the sides of the scoop; a pair of angle plates on the bail and so arranged that two webs of the angle plates together form a channel to receive the end of the stick, and the other two webs are juxtaposed, one above the other, and permanently secured to the bail; the two juxtaposed webs having approximately the width and length of the transverse portion of the bail; foot members permanently fastened to the stick at its end to facilitate a rigid connection between the stick and bail; the construction permitting the transmission of the downward stresses imposed by the stick directly through the bail to the scoop without shearing stresses imposed on the attaching bolts.
7. An assembly of the class described comprising, in combination, a ditcher stick; an excavating scoop having a bail extending transversely across the open top and secured to the sides of the scoop; a pair of angle plates on the bail and so arranged that a channel is provided to receive the ditcher stick; two webs of said angle plates being juxtaposed, one above the other, and permanently secured to the bail; right angular foot members permanently secured to the stick on each side thereof at its end and each having a leg to extend over and lie on the web of the uppermost angle plate; bolts substantially parallel to the longitudinal axis of the stick for connecting the stick and scoop together and passing through the foot members, the two webs and the bail; the construction permitting the transmission of the downward stresses imposed by the stick directly through the bail to the scoop without shearing stresses imposed on the attaching bolts.
8. An assembly of the class described comprising, in combination, a ditcher stick comprising two spaced, parallel structural steel members permanently secured together; right angular foot members secured to the inside and outside of each of the parallel members at the lower end of the stick; a scoop; an angle plate extending at right angles to and above the scoop and secured thereto and abutting the lower end of the stick; and means passing through the foot members for removably connecting the scoop with said stick, so that no shearing stresses are imposed on said connecting means during use of the scoop.
9. An assembly of the class described comprising, in combination, a ditcher stick comprising two spaced, parallel channel members permanently secured together; right angular foot members secured to the inside and outside of each of the channel members at the lower end of the stick; an excavator scoop having a bail; a pair of angle plates secured to the bail and so arranged, when the parts are assembled, that one web of each angle plate is adjacent to but outside of the stick, and the other two webs are juxtaposed, one above the other, and permanently secured to the bail; and bolts connecting the scoop by means of its bail with the foot members; the construction permitting the transmission of the downward stresses imposed

by the stick directly through the bail to the scoop without shearing stresses being imposed on the attaching bolts.

10. An assembly of the class described comprising, in combination, a ditcher stick; a removable excavator scoop; and connecting means therefor interposed between the lower end of the ditcher stick and the scoop and located well above the top of the scoop and so constructed and arranged that a few bolts, forming a part of said connecting means and subjected to tension only, are adequate to prevent play between the connected parts under the reversing stresses set up during excavation; said bolts being the only parts which need to be removed to permit detaching of the scoop.

11. An assembly of the class described comprising, in combination, a ditcher stick; an excavator scoop; a bail rigidly secured to the scoop and connecting means for the stick and scoop including an enlarged foot or base for the stick; a rigid reinforcement for the bail serving to brace the bail against buckling and to prevent play of the scoop relative to the stick; and fastening elements passing between the enlarged foot of the stick and the reinforced part of the bail.

12. An assembly of the class described comprising, in combination, a scoop; a ditcher stick composed of two spaced, parallel members rigidly secured together; a channel-like structure composed of members permanently secured to and above the scoop to provide a recess in which the end of the stick fits; and a clamping bolt extending between the sides of the channel-like structure and gripping the end of the stick, thus preventing abrasion between the stick and the floor of the channel.

13. An assembly of the class described comprising, in combination, a ditcher stick composed of two spaced, parallel members permanently secured together; a scoop; a pair of angles rigidly secured to and above the scoop and also secured to each other, and having two upstanding flanges or webs forming a channel in which the end of the stick fits; and a clamping bolt extending between said flanges or webs and gripping the end of the stick, thus preventing abrasion between the stick and the floor of the channel.

14. An assembly of the class described comprising, in combination, a ditcher stick; an enlarged foot or base permanently secured to the stick; a scoop; a structure secured to and above the scoop and forming a channel to receive the end of the stick; a clamping bolt extending between the sides of the channel and gripping the end of the stick, thus preventing abrasion between the stick and the floor of the channel; and a spacer tube surrounding the clamping bolt and extending between the sides of the channel to resist buckling of said base.

15. An assembly of the class described com-

prising, in combination, a ditcher stick; a scoop; a bail rigidly connected to the sides of the scoop and extending transversely over the top of the scoop and having a pair of flanges secured thereto and arranged so that a recess is provided for the end of the ditcher stick; bolts parallel to the longitudinal axis of the stick for uniting the stick and scoop by means of said bail; said bolts being relieved of shearing stresses arising from excavation by the flanges which bear against opposite sides of the stick.

16. An excavator scoop comprising, in combination, a scoop body; a bail rigidly connected to the sides of the body and extending transversely over the top of the scoop; a pair of angle plates both secured to the bail above the transverse portion of the same to reinforce and prevent buckling of the bail; and a brace secured to the upper part of the end wall of the scoop and also to one of the flanges of the angle plates and forming a generally triangular truss with the scoop and bail.

17. An excavator scoop comprising, in combination, a scoop body; a bail rigidly connected to the sides of the body and extending transversely over the top of the scoop; a pair of angle plates both secured to the bail above the transverse portion of the same to reinforce and prevent buckling of the bail; scoop-bracing means; and a shoulder secured to the end wall of the scoop to provide means for connecting the scoop bracing means with the scoop-supporting structure.

18. An assembly of the class described comprising, in combination, a ditcher stick; a scoop; means for removably fastening the scoop upon the lower end of the ditcher stick; a scoop brace permanently secured to the ditcher stick at an intermediate point thereof; a shoulder on the end wall of the scoop; a foot member permanently secured to the end of the scoop brace; and means passing through the foot member and the shoulder for removably fastening the scoop brace to the scoop.

19. An assembly of the class described comprising, in combination, a ditcher stick; a scoop; connecting parts therefor; bolts for removably fastening the scoop on the end of the ditcher stick; a scoop brace carried by the ditcher stick; connecting parts for the scoop brace and the scoop; and bolts for removably fastening the scoop brace and scoop; each set of bolts extending substantially parallel to the part which is connected thereby to the scoop and being subjected to no shearing stresses when the scoop is in use.

20. In combination, a standardized ditcher stick having a base or foot which is enlarged to transmit power; a set of excavating scoops of different widths to excavate trenches and the like; each scoop of said set having a recess of proper dimensions to receive the en-

larged base or foot of the standardized ditcher stick; and removable fastening elements to hold one of the scoops upon the stick.

5 21. In combination, a standardized ditcher stick; a set of excavating scoops of different widths; and bolts for connecting any one of

the scoops to the end of the ditcher stick; said bolts extending parallel to the ditcher stick and being subjected to tension only 10 when the scoop is in use.

In testimony whereof, I have signed my name to this specification.

ROBERT REX DOWNIE.
